APPLIANCE FOR WAVING HAIR

Joseph V. Slavick, Washington, D. C.

Application June 25, 1934, Serial No. 732,366

16 Claims. (CL 132—36)

My invention relates to apparatus for waving or curling hair upon the human head.

An important object of the invention is to provide apparatus of the above mentioned character, which is extremely simple in construction, 5 cheap to manufacture and which may be quickly and easily manipulated.

A further object of the invention is to provide a pad to be applied to the head for use in connection with a clamp, and which will serve to effectively prevent steam and heat passing to 10 the scalp.

A further object of the invention is to provide simple and reliable means for connecting the casing with the clamp.

A further object of the invention is to provide simple and reliable means for rotating the curling element or spool within the casing and locking the same against rotation to retain the 15 wound hair under proper tension.

A further object of the invention is to provide means whereby heat rays from a lamp may be employed in heating the prepared wound hair, to effect curling.

Other objects and advantages of the invention 20 will be apparent during the course of the following description.

In the accompanying drawing forming a part of this application and in which like numerals are employed to designate like parts throughout 25 the same,

Figure 1 is a perspective view of a hair waving appliance embodying my invention, showing the parts assembled.

Figure 2 is a similar view, showing the parts 30 separated.

Figure 3 is a central vertical longitudinal section through the assembled appliance.

Figure 4 is a transverse section taken on line 40 4—4 of Figure 3.

Figure 5 is a perspective view of a modified form of an appliance embodying the invention.

Figure 6 is a transverse section taken on line 45 6—6 of Figure 5, and

Figure 7 is a plan view of the pad.

Attention being called first to Figures 1 to 4 inclusive, the numeral 10 designates an elongated pad, which is formed of compressible rubber, and is adapted to be placed upon the scalp. This 50 pad has a substantial thickness and is provided upon its upper surface with an upstanding rib or flange 11, formed of the same material as the pad 10 and preferably integral therewith. The pad and rib are provided with a longitudinal vertical slit 12. This slit passes through the bot-

tom face of the pad 10 and the top face of the rib 11, and terminates at points spaced from the ends of the rib 11. This rib constitutes a marginal lip extending about the slit 12, as shown.

The numeral 13 designates a clamp as a whole, 5 embodying elongated sides 14, preferably formed of metal, and having their inner longitudinal edges bent upwardly, producing flanges 15, which face outwardly from each other and are curved in cross-section. Arranged beneath the sides 14 are rigid heat insulating strips 16, preferably formed of bakelite. The insulating strip 16 is spaced from each side 14, and a spacing block 17 is arranged between these parts, and these several elements are rigidly held together by suitable means, such as a rivet 18. A U-shaped hinge element 19 has its closed end mounted upon one end of one side 14. This hinge element embodies upper and lower leaves 20 and 21. The lower leaf extends beneath the side 14 and between it and the adjacent insulating strip 16 and the leaves, sides 14 and insulating strip 16 are rigidly secured together by a rivet 22 or the like. The leaves 20 and 21 are arranged above and beneath the adjacent end of the other side 25 14, and these elements are pivotally connected by a rivet 23, which passes through the leaves 20 and 21, the side 14, and insulating strip 16. The numeral 24 designates a U-shaped latch, embodying upper and lower leaves 25 and 26. 30 The upper leaf 25 is provided with an upstanding ear or extension 27, adapted to be engaged by the finger in opening or closing the latch. The free ends of the leaves 25 and 26 are arranged above and below the free end of one side 14, 35 and are pivotally connected therewith by means of a rivet 28 or the like, passing through these leaves, the side 14, and the adjacent insulating strip 16. The closed end of the latch 24 is adapted to be moved over an extension 29, formed 40 upon the free end of the companion side 14, thereby locking the movable side in the closed position parallel with the companion side 14. Adjacent to the extension 29, a spacing block 30 45 is arranged beneath the side 14, and a rivet 31 or the like serves to rigidly connect this side 14, block 30, and the insulating strip 16.

The numeral 32 designates a preferably cylindrical casing which is preferably formed of metal and is provided at one end with a head 33, having a centrally arranged contracted opening 34 formed therein. The casing 32 is also provided in its lower portion with an elongated slot 35, which extends from the open end of the elongated casing to a point 36, arranged near and 50

spaced from the head 33. Rigidly attached to the upper portion of the casing 32, adjacent to its opened end, and opposite the slot 35, is an inwardly projecting locking tooth or lug 37, as shown.

The numeral 38 designates a rotatable curling element or spool, which is circular in cross-section and increases in diameter toward its opposite ends. This spool is provided upon its opposite ends with parallel flanges or wheels 39 and 40, rigidly attached thereto. The flange or wheel 40 is provided upon its periphery with spaced notches 41. The flanges or wheels 39 and 40 are adapted for insertion within the cylindrical elongated casing 32 and have a slightly smaller diameter than the interior diameter of this casing. A recess 42, formed square in cross-section, is formed in the central portion of the flange or wheel 39 and the adjacent end of the curling element or spool 38 and is adapted for alignment with the opening 34. A key 43 is adapted to be inserted through the opening 34 into the recess 42 and this key is used to turn the curling element or spool when arranged within the casing 32.

The casing 32 is not provided with heating means permanently attached thereto, and any well known type of heating device may be detachably applied to the casing 32, such as an electrical heater of the clamp type, as shown in Letters Patent 1,455,696, embodying electric heaters A and B. By having the electric heater detachable, when it is removed from the casing, such heated casing will cool much quicker, thus allowing the hair to cool quicker. The casing constitutes a substantially closed space for the hair, and since the wrapper is omitted from the hair, the uncovered hair will also heat quicker. That portion of the solution which is vaporized is held in the casing in contact with the hair, and freely passes around the hair to act upon all portions thereof, while the hair remains spaced from the casing. The heater is applied to the casing and the current turned on and it takes about two minutes for the electric heater to reach boiling point and the heater at this temperature remains on the casing for about one minute. This is sufficient to heat the hair properly. The heater is then bodily removed and the casing then cools, the hair tightening up upon the falling temperature. The time that the hair is to remain upon the curler, during the cooling period, depends considerably upon the structure of the hair, and the longer the hair remains wound upon the curler, during the cooling period, the tighter will be the curl.

The use of this form of the appliance is as follows:

The operator selects a lock of hair and applies thereto a softening solution and this lock so treated is passed through the slit 12 in the pad 10 until the pad is brought into firm engagement with the scalp, the lock having its strands arranged so that the lock is flat or that portion of the lock is flat which is positioned within the slit 12. With the lock extending above the slit and the pad 10 in firm engagement with the scalp, the clamp 13 is now applied to the top of the pad, in the open position, and its stationary side is brought into engagement with one side of the rib 11, the curved flange 15 engaging such side of the rib. The companion side of the clamp carrying the latch 24 is now swung to the inner position and when becoming parallel with the first side, the latch 24 is swung over the extension 29. The flanges 15 of the two sides 14 now firmly en-

gage and compress the slit rib 11, and this slit rib will now firmly engage the flat lock, and yield in such engagement therewith, whereby this slit is completely closed and any steam prevented from passing through the slit to the scalp, while the pad 10 will prevent overheating of the scalp. With the pad and clamp thus mounted on the scalp, the operator places the free end of the lock upon the spool and turns the spool to wind the lock thereon, such lock being previously treated with a softening solution, which is suitable for the type of hair being waved. The operator regulates the tightness of the winding during the rotation of the curler or spool and when the winding is practically completed the spool is placed upon the top of the clamp 13 in substantial alignment with the slit 12. Instead of winding the lock on the spool by rotating the spool, the lock may be spirally wound upon the spool in whole or part. It is desired that the hair be evenly wound upon the spool so that it will be at all times spaced from the casing 32 with the spool placed on top of the clamp. As explained, the open end of the casing 32 is brought to the flange or wheel 39, and the casing is inclined and moved over the top of wheel 39 so that the tooth or lug 37 will clear the wheel 39, and at about the same time, the edges of the slot 35 are brought into engagement beneath the longitudinal flanges 15 and the casing is then moved forwardly toward the flange or wheel 40 in parallel relation with the clamp 13. When the open end of this casing is disposed adjacent to the wheel 40, the key 43 is inserted into the recess 42 and the spool is slightly turned to obtain the desired final tension on the lock, and while the spool is held against rotation, the tooth or lug 37 is inserted into the adjacent notch 41, and this locks the spool to the casing against rotation. Instead of turning the curler by the key 43 it may be turned by the operator turning the wheel 41. With the parts thus assembled, it will be seen that the spool or curler is supported in the casing in concentric relation to the casing and hence the hair is retained spaced from the casing and does not contact therewith. This eliminates the necessity of applying the usual wrapper to the hair, to prevent burning, where the hair would otherwise contact with the heater. The wheels 39 and 40 have substantially a sliding fit in the casing 32, and substantially cover the ends of this casing, the slot 35 being covered by the clamp, whereby the casing is substantially closed. An electrical heater of any well known or preferred type is now applied to the exterior of the casing 32, to heat the same, which heat is transmitted to the interior of the casing and is transmitted to the wound hair by radiation alone and not by contact. Since the wound hair treated with the softening solution is enclosed within the substantially closed casing, the solution will evaporate sufficiently slowly to cause the proper curling of the hair. At the end of the heating period, the electrical heating device is separated from the casing 32 and the casing removed from the clamp, by a longitudinal movement, but the spool will not move longitudinally with the casing since the wheel 40 will engage the ends of the flanges 15. After the casing is removed, the hair is unwound from the spool, which is separated from the clamp, the clamp removed from the pad, and the pad separated from the lock.

In Figures 5 and 6, I have shown a modification of the appliance. In this modification, a pad 44 is provided which is to be applied to the

scalp. This pad is formed of compressible rubber and corresponds to the pad 10. This pad is provided upon its upper face with a rib 45, integral therewith and a longitudinal slit is formed 5 through the rib and pad and terminates at points near and spaced from the ends of the rib 45. Flanges 47 preferably formed of metal are provided and these flanges are curved in cross-section and face outwardly and the flanges embody 10 bases 48 which are imbedded in the material of the pad 44 upon opposite sides of the slit. Particular attention is called to the fact that the flanges and their bases terminate at the ends of the rib 45, whereby the extremities or ends of 15 the pad are left with their normal transverse elasticity. This permits the spreading of the flanges 47 and the slit 46 for the insertion of the lock of hair.

The numeral 49 designates an elongated cylindrical casing identical with the casing 32 except that the casing 49 is formed of transparent or light transmitting material such as glass. The metal tooth or stud 37 is attached to the open end of the casing 49 and the casing has the longitudinal slot 35 in its lower portion and the opening 34 for the key and the opposite end of the casing is open. The casing receives the same curling element or spool.

In the use of this form of the implement, the lock is passed through the slit 46 and the pad placed firmly upon the scalp. The lock is now wound upon the spool by rotating the spool or by winding the lock spirally about the spool and the spool is now placed on top of the pad 48, in alignment with the slit 46. The transparent casing 49 now has its open end applied over the wheel 39, and the edges of its longitudinal slot will engage beneath the flanges 47 and the casing 49 is then moved forwardly in parallel relation to the pad until its open end is brought adjacent to the notched wheel 40. The spool may now be turned within the casing to adjust the tension of the hair and the tooth or lug 37 then moved into the notch 41 to lock the spool against rotation. 45 When the casing 49 is applied to the flanges 47, it forces them inwardly sufficiently, to compress the rib 45 and close the slit 46. A source of light, such as any lamp, reflecting or otherwise, producing heat rays is now arranged suitably near 50 the transparent casing and the heat rays will pass through the casing and heat the wound hair having the softening solution applied thereto for producing a satisfactory permanent wave. I preferably employ a lamp which will produce infra red rays or violet rays. The heat rays suitably heat the hair. By heating with these rays, all of the disadvantages encountered in connection with electric heaters are dispensed with, and I can also use a weaker softening solution as applied to the hair. I have found that the heat rays from the lamp should be applied to the hair for about five to thirty minutes. The infra red rays or violet rays not only heat the hair for curling but are beneficial to the hair structure. 60 After the hair has become properly heated for a suitable length of time, it is allowed to cool on the curler, the casing removed, and the hair unwound from the curler.

It is to be understood that the forms of my invention herewith shown and described are to be taken as preferred examples of the same, and that various changes may be made in the shape, size and arrangement of parts of the apparatus, and changes may be made in the order of the 70 steps of the method, without departing from the 75

spirit of the invention or the scope of the subjoined claims.

Having thus described my invention what I claim is:

1. In a hair curling appliance, a pad provided upon its upper surface with flanges, between which the hair is passed, a clamp removably mounted upon the upper surface of the pad and including sides to engage the flanges to force the same inwardly to cover the slit, a casing removably mounted upon the clamp, and a curler for arrangement within the casing and being adapted to have the hair wound thereon and to hold the hair spaced from the casing. 5

2. In a hair curling appliance, a pad having an opening formed therein for the passage of hair, a clamp removably mounted upon the pad and including heat insulating elements engaging the pad, a casing removably mounted upon the clamp, and a curler for arrangement within the 10 casing and adapted to have the hair wound thereon and to retain the same spaced from the casing. 20

3. In a hair curling appliance, an elongated clamp having sides provided with flanges, an elongated casing having a longitudinal slot providing edges to engage with the flanges, and a curler mounted within the casing and adapted to have the hair wound thereon and to retain the same spaced from the casing. 30

4. In a hair curling appliance, an elongated clamp including spaced sides provided with spaced upwardly projecting flanges having laterally extending parts, and an elongated casing having one end open and provided with a longitudinal slot 35 passing through the open end, said slot receiving the flanges, said casing being interlocked with the flanges against relative vertical movement, and a curler adapted for insertion within the elongated casing through the open end. 40

5. In a hair curling appliance, an elongated casing having an end opening and an elongated slot for the passage of hair, a rotatable elongated curler provided near its ends with wheels, the curler being adapted for insertion into the elongated casing through the end opening and the wheels engaging the inner surface of the casing to retain the curler spaced from such inner surface, one wheel being arranged adjacent to the end opening and having notches, a locking element carried by the casing adjacent to its end opening for insertion within a selected slot for holding the curler against rotation, and means operated from the exterior of the casing to turn the curler before it is held against rotation. 50

6. In a hair curling appliance, a casing having an end opening and a longitudinal slot, an elongated curler having wheels near its ends, one wheel having notches, the curler being adapted for insertion into the casing through the end opening, and a tooth secured to the casing near its end opening and adapted for insertion within a selected notch. 60

7. In a hair curling appliance, a casing having an end opening and a longitudinal slot, an elongated curler having spaced wheels, one wheel having notches, the curler being adapted for insertion into the casing through the end opening and the wheels having substantially a sliding fit within the casing, and an inwardly projecting tooth secured to the casing near its end opening for insertion within a selected notch. 70

8. In a hair curling appliance, a casing having an end opening and a longitudinal slot, an elong- 75

gated curler having spaced wheels, one wheel having notches, the curler being adapted for insertion into the casing through the end opening, an inwardly projecting tooth carried by the casing and adapted for insertion within a selected notch, a hair clamp arranged beneath the casing and having a part for insertion within the slot, and a pad arranged beneath the clamp.

9. In a hair curling appliance, an elongated 10 casing having an end opening and a longitudinal slot, a pad having an opening for the passage of hair, flanges secured to the pad for insertion within the slot and having lateral extensions to engage with the inner surface of the casing, and 15 a curler for insertion within the casing through the end opening.

10. In a hair curling appliance, a clamp including elongated sides having laterally directed flanges extending longitudinally of the sides, a 20 casing having one end open and provided in its lower portion with a longitudinal slot, said slot having a width less than the diameter of the casing and affording spaced longitudinal edges which are adapted to engage beneath the flanges 25 so that the casing is locked to the flanges against relative vertical separation and is capable of moving longitudinally with relation to the flanges, a locking tooth attached to the casing, a curler having wheels, one wheel having notches adapted 30 to receive the locking tooth, the curler being adapted to be arranged upon the clamp and the casing brought into interlocking engagement with said flanges and moved longitudinally over the curler so that the wheels enter the casing and the 35 locking tooth is inserted within a selected notch.

11. In a hair curling appliance, a clamp including elongated sides having laterally directed flanges extending longitudinally of the sides, a casing having one end open and provided in its 40 lower portion with a longitudinal slot, said slot having a width less than the diameter of the casing and affording spaced longitudinal edges which are adapted to engage beneath the flanges so that the casing is locked to the flanges against 45 relative vertical separation and is capable of moving longitudinally with relation to the flanges, a locking tooth attached to the casing near its forward open end, a curler having wheels near its ends, one wheel having notches adapted to receive 50 the locking tooth, the curler being adapted to be arranged upon the clamp and the casing brought into interlocking engagement with said flanges and moved longitudinally over the curler so that the wheels enter the casing and the locking tooth 55 is inserted within a selected notch, and means operated from the exterior of the casing to turn the curler before the locking tooth is inserted within the notch.

12. In a hair curling appliance, a clamp 60 embodying sides having upwardly projecting flanges having lateral extensions, a curler having wheels at its ends and having one wheel provided with

notches, an elongated casing having a longitudinal slot and spaced longitudinal edges, said edges being adapted to be arranged beneath the lateral extensions of the flanges and the casing moved longitudinally of the flanges so that the 5 casing is locked to the flanges against relative vertical separation, the wheels engaging the inner wall of the casing to retain the curler in a substantially central position within the casing, and a locking tooth secured to the forward end of 10 the casing and disposed generally opposite the slot and adapted for insertion within a selected notch upon the longitudinal movement of the casing with relation to the notched wheel.

13. In a hair curling appliance, a casing having 15 an opening adjacent to one end thereof and a longitudinal slot, a clamp having means for insertion within the slot to hold the clamp and casing against lateral separation and permitting of relative longitudinal movement between the 20 casing and clamp, a curler for insertion into the casing through the end opening thereof, means to turn the curler, and means to hold the curler against turning movement.

14. In a hair curling appliance, a casing having 25 an opening adjacent to one end thereof and a longitudinal slot, a clamp having means for insertion within the slot and holding the clamp and casing against lateral separation and permitting of relative longitudinal movement between the 30 casing and clamp, and a curler for insertion into the casing through the end opening thereof.

15. In a hair curling appliance, a clamping device for engagement with the hair, an elongated 35 casing removably mounted upon the clamping device and having an opening at one end and a longitudinally extending slot, a curler to be inserted within the elongated casing through the opening in the end thereof, said curler being 40 adapted to have the hair wound thereon and provided with wheel or wheels to engage with the casing and retain the hair spaced from the casing, means to turn the curler while within the casing to place the hair under suitable tension, 45 and means to hold the curler against turning movement in one direction.

16. In a hair curling appliance, a clamping device for engagement with the hair, an elongated 50 casing removably mounted upon the clamping device and having an opening at one end and a longitudinal slot, flanges for preventing the relative turning movement of the casing with respect to the clamping device, a curler for insertion within the casing through the opening at its end 55 and adapted to have the hair wound thereon and having wheel or wheels engaging the casing to retain the hair spaced from the casing, means to turn the curler while within the casing to place the hair under tension, and means to hold the 60 curler against turning movement in one direction.

JOSEPH V. SLAVICK.
